ATTORNEY

UNITED STATES PATENT OFFICE.

JEFFERSON DAVIS PACE, OF SHREVEPORT, LOUISIANA.

WELL-DRILLING BIT.

Application filed May 7, 1921. Serial No. 487,608.

To all whom it may concern:

Be it known that I, JEFFERSON D. PACE, a citizen of the United States, residing at Shreveport, in the parish of Caddo and State of Louisiana, have invented new and useful Improvements in Well-Drilling Bits, of which the following is a specification.

This invention has reference to well-drilling bits, and its object is to provide a bit for the expeditious forming of deep well bores, especially oil well bores, and at the same time enabling the operator to obtain samples of the formation being drilled in order that its character may be ascertained.

In accordance with the invention, there is provided a rotary shoe so arranged that the main drill pipe may be screwed into it, the other end of the shoe being formed with circular series of teeth or cutters. The lower end of the shoe is closed except for the presence of a central hole to receive a testing or core barrel and through the closed end there is formed a number of holes so that water may pass down the inside of the drill pipe about the core barrel and through the holes to the exterior of the drill pipe and there escape upwardly. The core pipe is provided with a gravity valve which will automatically close down tight and automatically holds the core in the core barrel when raising the drill to examine the core. The arrangement is such that water does not come in contact with the core, thereby overcoming certain difficulties which have been experienced with other arrangements for obtaining samples of the many formations encountered in putting down wells.

The invention will be best understood from a consideration of the following detailed description taken in connection with the accompanying drawing forming part of this specification, with the understanding, however, that the invention is not confined to any strict conformity with the showing of the drawing, but may be changed and modified so long as such changes and modifications mark no material departure from the salient features of the invention as expressed in the appended claims.

In the drawing:

Fig. 1 is an elevation of the rotary shoe and the lower end of the drill pipe to which the shoe is attached.

Fig. 2 is a longitudinal diametric section of the structure shown in Fig. 1, but broken

intermediately to indicate that the showing of Fig. 2 is much more extensive than the showing of Fig. 1.

Fig. 3 is a bottom plan view of the structure shown in Fig. 1.

Fig. 4 is a section on the line 4—4 of Fig. 2.

Fig. 5 is a fragmentary view of the upper end of the core pipe showing the valve 65 lifted.

Fig. 6 is a section on the line 6—6 of Fig. 5.

Referring to the drawing, there is shown a hollow drill pipe 1, provided at the lower end with a screw-thread 2 to receive a drill shoe 3 suitably threaded to correspond to the screw-thread 2. The shoe 3 has at one end, the upper end, a socket to receive the hollow rod or drill pipe 1, and the parts are so proportioned that the end of the shoe remote from the socket provides a head 4 of suitable thickness not only to withstand the work to which it is subjected, but to provide room for the formation of cutting teeth 5 arranged in circular series. These teeth, in the showing in the drawings, are right hand teeth.

Extending through the head 3 in the direction of the length thereof, is a series of passages or perforations 6 communicating with the interior of the pipe 1 through the head 4, and close to the throats of the teeth.

The head is provided with a threaded passage which receives the threaded lower end 7 of a core barrel 8 rising up in the pipe 1 to a desired height, leaving ample space about the core barrel. At the upper end the core barrel is provided with a valve 9 having a laterally expanded head 10 of a size to close the upper end of the core barrel. The valve 9 has an extended skirt portion 11 fitting snugly, yet freely, in the core barrel and this skirt is provided on opposite sides with elongated slots 12, traversed by a pin 13, holding the valve 9 in place in the upper end of the core barrel, but permitting a considerable movement of the valve lengthwise of the core barrel, and also permitting communication between the interior of the valve 9 and the interior of the drill pipe.

The core barrel is provided at the lower end with a short section 8^a which is screwed into the threaded passage of the head 4 and terminates in an outwardly beveled cutting edge 14 allowing the core to rise in the core

barrel as the drilling proceeds. Between the section 8^a and the bottom of the main section of the core barrel is a core supporting ring 14^a, having a smaller internal diameter than the section 8^a and barrel 8, but there rounded and loose in the barrel so as to readily rotate therein independently thereof.

In order to dispose of the chips and other débris as the drilling is performed, water is forced down through the drill pipe or rod 1, thereby tightly closing the valve 9 and preventing access of water to the core, the water readily escaping through the passage 6 to the exterior of the drill pipe or rod at its lower end, and finding its way up outside of the drill pipe to the surface of the ground. In the meantime the advance of the core into the core barrel is in no wise interfered with, since air confined in the core barrel and displaced by the advancing core, will escape through the upper valved end of the core barrel through the slots of the valve 9 and the valve will readily drop by gravity onto the upper end of the core barrel whenever the pressure within the core barrel drops to a sufficient degree.

When the drill rod or pipe is raised for the purpose of removing and examining the core, the valve at once closes and water which may be in the drill pipe escapes through the holes 6 without affecting the core itself. The gravity valve 9 is so constructed as to close air-tight when the pipe 1 is being raised, thereby holding the core by suction from dropping out of the pipe. This produces a simple and efficient arrangement for the purpose, far superior to core barrel valves held closed by springs.

The inner end of the cutter section 8^a is spaced from the lower end of the core barrel and said space forms a seat for the rotatable ring 14^a, which is of smaller internal diameter than the cutter section or the core barrel, and serves to hold the core in the barrel when once above the ring, and also prevents binding and buckling of the core. The section 8^a forms a cutter which extends below the lower ends of the openings 6, so that the water passing through said holes does not reach the core.

What is claimed is:

1. In a well drilling tool, a rotary hollow drill pipe having a terminal shoe body with cutting teeth on the lower end and passages therethrough for the outflow of water, said shoe body having a central core opening, and a core barrel secured therein and rising above the shoe body within the drill pipe, said core barrel having a check valve at its upper end preventing passage of water into the barrel, a cylindrical cutter section secured to and extending downwardly from the shoe body in alinement with the core barrel and terminating in an annular cut-

ting edge substantially at the same level as the cutting teeth on the shoe body and preventing water from entering the lower end of the core barrel when drilling.

2. A rotary core drilling tool comprising a hollow drill pipe, a shoe carried by the lower end of the pipe and provided with cutting teeth on its lower end, a core barrel carried by the shoe and open at its lower end, said core barrel extending upwardly from the shoe into the drill pipe and provided at its upper end with a slide valve having an expanded head which constitutes a closure for the upper end of the core barrel, and an extension for said core barrel extending downwardly from the shoe and provided with a cylindrical cutter extending to the bottom of the cutting teeth of the shoe, said valve and cylindrical cutter cooperating to prevent water from entering the core barrel.

3. In a rotary well drilling tool, a tubular pipe having a shoe secured to its lower end, said shoe terminating in a circular series of cutting teeth, a core barrel carried by and extending upwardly from the shoe concentric with the pipe, said core barrel being open at its lower end, means extending from the shoe and engageable with the soil formation to exclude water from the lower end of the barrel while drilling, said barrel being provided at its upper end with a longitudinally movable valve having a laterally expanded head to close the barrel against access of water through the upper end, said valve having longitudinally-extended slots for the passage of a retaining pin permitting the opening of the valve and preventing its escape from the core barrel, said slots extending above the top of the core barrel when the valve is raised to permit escape of the air from the interior of the barrel.

4. In a well drilling tool, a hollow drill pipe, a one-piece shoe with a screw socket into which the lower end of the pipe is screwed, said shoe having a circular series of cutting teeth at its lower end and provided with passages for the outflow of water, a core barrel concentric with and extending upwardly from the shoe into the hollow drill pipe and provided at its upper end with a gravity valve, means for retaining the valve in the core barrel with a limited longitudinal movement, and means extending below the shoe in alinement with the barrel and engageable with the soil formation being cut, said means together with the valve serving to exclude all water from the interior of the barrel while permitting the escape of air therefrom.

5. A rotary drilling tool comprising a hollow drill rod, a shoe carried by the lower end of the rod and provided with cutting teeth at its lower end, a core barrel carried by and extending upwardly from the shoe within the drill rod, a cutter section extend-

ing downwardly from the shoe to substantially the same depth as the teeth on the shoe and constituting a continuation of the core barrel, the lower end of the core barrel 5 and the upper end of the cutter section forming spaced shoulders defining a cylindrical space enclosed by the shoe body, and a ring freely and independently rotatable in said space and of smaller internal diameter than 10 the core barrel whereby to sustain the core and to prevent binding and buckling of the same.

6. A rotary drilling tool comprising a hollow drill rod, a shoe carried by the lower 15 end of the drill rod and provided with cutting teeth on its lower end, and a head at an intermediate point, said shoe having a central threaded passage therethrough, a

core barrel having its lower open end screwed into said threaded passage upon one 20 side of the head, a core cutter screwed into the threaded passage upon the other side of the head and having a cutting edge extending substantially to the same depth as the cutting teeth on the shoe, the adjacent 25 ends of the core cutter and core barrel being spaced from each other to form a seat in the passage, a rotatable ring having a smaller internal diameter than the core barrel or 30 core cutter and mounted in said seat and adapted to guide and retain the core in the core barrel.

In testimony, that I claim the foregoing as my own, I have hereto affixed my signature.

JEFFERSON DAVIS PACE.
